UNITED STATES PATENT OFFICE.

SUSAN P. GATES, OF WALLA WALLA, WASHINGTON.

HOUSE-GOWN.

1,256,891.

Specification of Letters Patent. Patented Feb. 19, 1918.

Application filed May 20, 1916. Serial No. 98,900.

To all whom it may concern:

Be it known that I, SUSAN P. GATES, a citizen of the United States, residing at Walla Walla, in the county of Walla Walla 5 and State of Washington, have invented certain new and useful Improvements in House-Gowns, of which the following is a specification, reference being had to the accompanying drawings.

10 This invention relates to an improved house gown for women and has for its primary object to provide an improved construction of such a gown whereby the same will fit perfectly over the shoulders of the 15 wearer.

It is a more particular object of the invention to provide a sack gown having gussets set in the top of the shoulder portions and gradually tapering outwardly from the 20 neck scye to a point whereby the gown will be properly supported from the shoulders and prevented from pulling upwardly in the front.

It is an additional object of my invention 25 to provide a gown of the above type which may be made at substantially the same cost as the ordinary house gown and is very serviceable and convenient in practical use.

30 With the above and other objects in view, my invention consists in the novel features of construction, combination and arrangement of parts to be hereinafter more fully described, claimed and illustrated in the 35 accompanying drawing, in which,

Figure 1 is a perspective view showing my improved gown fitted upon a figure; and

Fig. 2 is an enlarged plan view of one 40 of the arms and shoulder portions of the garment.

Referring in detail to the drawing, 5 designates the body of the garment which is of sack form or, in other words, is not 45 made to conform to the outline of the figure upon which it is to be fitted. Loops 6 are sewed at their ends to the waist portion of the garment body to receive a suitable belt indicated at 7 which may be of the same 50 material as the garment, or of a different material, and is provided on its extremities with suitable fastening means whereby the same may be connected around the waist 55 of the wearer. The neck line of the garment, indicated at 8, merges into the opposite sides of the deep V-shaped cut or

open front portion designated by the numeral 9. The opposite edges of this open V-shaped front are provided with suitable eyelets to receive a tie string 10, whereby 60 the lower portion of the V-shaped open front may be closed.

In the top of each shoulder portion of the garment, a gusset 11 is inserted. These gussets are of V-shaped form and the wider 65 ends thereof form continuations of the neck line of the garment while the pointed ends of the gussets terminate substantially at the outer end of the shoulder line. The garment is provided with short sleeve lengths 70 12 and suitable braid or other trimming, indicated at 13, is sewed onto the garment at the edges of the gussets 11, the inner ends of the sleeves and the edges of the 75 neck and open front.

In the application of the garment in practical use, the same is fitted downwardly over the head of the wearer and the arms inserted through the sleeves in the usual manner. By means of the inserted gussets 80 11, the shoulder portions will fit perfectly and the dress will hang properly both in the front and in the rear. Thus, it will be seen that I have produced a very simply constructed and serviceable house garment which 85 will greatly improve the appearance of the wearer. The garment may also be very easily and quickly fitted upon the body of the wearer or removed. While in the illustrated embodiment of the invention I have 90 shown a plain type of house dress, it is apparent, of course, that the same may be ornamented or embellished in various ways known to the dressmaking art. The dress may also, of course, be made in various 95 sizes to fit different shaped figures. In view of the extreme simplicity of my improved house dress, it is further manifest that the same can be made at substantially the same expense as the ordinary garment 100 100 of this type.

Having thus fully described my invention, what I desire to claim and secure by Letters Patent is:—

A one-piece garment consisting of a sack-like body provided in its front portion with a V-shaped opening extending downwardly from the neck of the gown, and a fastener for connecting the opposite edges of said opening in spaced relation to the lower end 110 thereof, said body having short sleeves and V-shaped gussets inserted into the top of

each shoulder portion of the garment extending over the shoulder forwardly and rearwardly of its central portion, the wider ends of the gussets constituting continuations of the neckline of the garment and the points of the gussets terminating at the outer ends of the shoulder portions thereof.

In testimony whereof I hereunto affix my signature in the presence of two witnesses.

SUE P. GATES.
